UNITED STATES PATENT OFFICE.

BENJAMIN KELLOGG, OF PEORIA, ILLINOIS.

CAR-BRAKE.

SPECIFICATION forming part of Letters Patent No. 410,760, dated September 10, 1889.

Application filed April 9, 1887. Serial No. 234,250. (No model.)

To all whom it may concern:

Be it known that I, BENJAMIN KELLOGG, a citizen of the United States, residing at Peoria, in the county of Peoria and State of Illinois, have invented a new and useful Improvement in Car-Brakes, of which the following is a specification.

My invention relates to that class of car-brakes known as "automatic," and the improvement consists of the application, construction, combination, and arrangement of the devices used, as set forth in this specification, whereby the applying of the brakes on one car will automatically and expeditiously cause the brakes on the remainder of the cars of the train to be set, thereby averting accidents and promoting the efficiency of train service; and I make no claim to that portion of the device which has been known for years past as the ordinary common car-brake, but simply claim the method of applying power (generated by the rotary motion of the axle of the car-wheels) to said common car-brake for purposes and in the manner set forth in the accompanying drawings, in which—

Figure 1 is a direct view of the bottom of a car, showing all the rods and connections of said car-brake when out of gear. Fig. 2 is a vertical section of part of the mechanism, showing position of car wheel and axle by dotted lines. Fig. 3 is a direct bottom view of brake mechanism as it would appear with the car-trucks taken off with brakes set. Fig. 4 is a detailed view, in perspective, of a portion of hooked rod with guide block and stop. Fig. 5 is a detailed and sectional view of one of the shaft-boxes in which the shaft on which friction-pulley is attached turns. Fig. 6 is a detailed and sectional view of the other shaft-box in which the shaft on which friction-pulley is attached turns.

In the drawings, A represents a friction-pulley, which, being drawn in contact with the pulley B, which is fixed on the axle of the car-wheel, causes said friction-pulley A to revolve.

On the same shaft on which friction-pulley A is attached is the cog-wheel C, which, when the friction-pulley A is drawn against pulley B, engages with the cog-wheel D on the reel-

shaft E, causing said reel-shaft to revolve by means of the rotary motion of the axle of car-wheel. On the said reel-shaft E are attached the two chains F and G. The chain G is attached to brake-rod H and sets the brake on the car. The chain F is attached to the levers I I' by the rods J and J' and in connection with the block-pulley K. When said chain F is wound on the reel E, it draws the levers I and I' inwardly from each end of car, and with these levers the chains attached, viz: L L' L² L³. The said chains L L' L² L³ are made of wrought-iron, with the exception of one link situated where the chain is attached to lever, which is made of cast-iron or other like material, for the purpose of causing the chain to break at that place should the train break apart.

On the levers at the same place where chains are attached are the hooks M M' M² M³, so that should train break apart and cause chains to be broken in aforesaid weak link the brake could be connected by means of the said hooks until train arrived at its destination.

The lever I or I' is prevented from sagging by means of the guide-stirrup N in Fig. 3, and prevented from pulling entirely out, should train break apart, by the guard O in Fig. 3, which is made sufficiently strong to withstand the strain it is exposed to.

The shaft-boxes P and Q are each constructed of three pieces (see Figs. 5 and 6) respectively, of which a represents a plate of iron hollowed in the center, and b represents a plate of iron with a slot cut in its center, and e represents a piece of iron through which the shaft d turns, which projects through the slot in plate b, and the flanges of which fit in the hollow of plate a, which allows shaft-box e to be moved in said slot and prevents binding in shaft-box e.

The spring R is used for the purpose of automatically throwing the cog-wheels C and D and the friction-pulley A out of gear.

Attached to box P, in which shaft of friction-pulley turns, is the chain S, which divides into two parts at pulley-block T, one part S' running over said pulley-block and connecting with hooked rod U, which projects three or four inches from end of car.

The other portion connects with rod U' , which projects three or four inches from the other end of car. Attached to rod U' is the chain V , which connects with brake-spindle, making 5 three places from which brake may be applied, viz: first, from brake-wheel on top of car; second and third, from each or either end of car by connecting the hooked rods v and v' with either of the chains on adjacent car to 10 correspond with chains $L L' L^2 L^3$, heretofore described. On said rods are the enlargements or stops X' and guide-block X to prevent their pulling out should train break apart. (See Fig. 4 for detail view of same.) 15 It is not absolutely necessary to always use the entire mechanism herein described, it being desirable in some cases (notably street-railways and other railways having curves of a very short radius) to dispense with the 20 levers $I I'$, and instead of them to carry the rods $J J' U U'$ nearly under the middle or center of the bottom of the car. The object of this is to obviate the possible difficulty of having the chains connecting two cars tightening on short curves. 25

Operation: When applying this brake, the brake-wheel y on the top of car is turned, winding the chain V on the brake-spindle of said brake-wheel and causing the friction-pulley A to be brought in contact with the 30 wheel B on the axle of the car-wheel, and also bringing the cog-wheels C and D into gear and causing the reel E to turn, winding the chains F and G . The chain G draws the 35 brake-rod H and sets the brake, as on ordinary car-brakes. The chain F causes the levers I and I' to be drawn inward, pulling the chains L , L' , L^2 , and L^3 , which are connected with the hooked rods to correspond 40 with v and v' on adjacent cars, causing the friction-pulleys on said adjacent cars to be brought into gear and so setting the brakes on them, and they in turn setting those on cars next to them, and by this means setting

the brakes throughout the train by applying 45 force to any one brake-wheel on train.

What I claim as my invention, and desire to secure by Letters Patent, is—

1. In combination, in a car-brake, the fixed pulley B , attached to car-axle, the friction-pulley A , the cog-wheels C and D , and the reel-shaft E , these parts being combined and operated substantially in the manner and for the uses herein set forth. 50

2. In combination, in a car-brake, the shaft-boxes P and Q , which allow the shaft passing through them to be drawn toward and away from the friction-pulley A and cog-wheel D without binding, substantially as set forth. 55

3. In combination, in a car-brake, the levers $I I'$, the hooks $M M' M^2 M^3$, the stop O , and the chains $L L' L^2 L^3$, combined and operated substantially in the manner and for the uses herein set forth. 60

4. In combination, in a car-brake, the rods $U U'$, with the chains attached thereto, together with the stop X' and the guide-block X , combined and operated substantially in the manner and for the uses herein set forth. 65

5. In combination, in a car-brake, the bifurcated chains $S S'$, connecting the rods $U U'$ with the axle-box P , one portion of said chain pulling over a block-pulley T , combined and operated substantially as herein set forth. 70

6. In combination, in a car-brake, the bifurcated chain F , connecting the rods $J J'$ with the reel-shaft E , one portion of said chain pulling over a block-pulley K , combined and operated substantially as herein set forth. 75

7. In the herein-described car-brake, the spring R , arranged to throw the friction-pulley out of gear when the brakes are released, operated substantially as herein set forth. 80

BENJAMIN KELLOGG.
